SPRINGING FOR RAILWAY TRUCKS

Isaac M. Chambers, Narberth, Pa.

Application October 10, 1941, Serial No. 414,404

8 Claims. (Cl. 105—197)

This invention has general reference to railway trucks, preferably, of the bolster type wherein each end of the bolster is spring supported from below within the window of the corresponding side frame of the truck, and alignedly related springs likewise support the wheel axle bearing boxes from below.

An important feature of this invention is the provision of a novel arrangement of springing, of the above referred to general type, including a main and longitudinally spaced lappingly arranged springs mounted in the truck side frame so that low-amplitude high-frequency shocks are absorbed by the secondary springs, while the high-amplitude low-frequency shocks are absorbed by the main spring.

Another feature of this invention is a truck springing, of the type indicated in the preceding paragraph, wherein the main and secondary springs are all of the semi-elliptic species and serially mounted, while the ends of the main spring react on an individual secondary spring, whereas said secondary springs have the respective inner ends thereof fulcrumed in the side frame, proximate the center line of the truck, with their outer ends fulcrumed directly below the journal boxes.

A further feature is the provision, in combination with leaf springing of the above stated character, of over-stress preventing and safety-stop means in the truck side frame for contact by the main spring and the secondary springs respectively.

Other features with ancillary advantages of this invention will become apparent from the following detailed explanation of the preferred embodiment thereof, shown by the accompanying two sheets of illustrative drawings, wherein like reference characters designate corresponding parts in all the views, while the concluding claims more particularly define the items of novelty over the prior art.

In the drawings:

Fig. 1 is a part vertical section and part side view of a railway truck including the novel springing of this invention.

Fig. 2 is a staggered plan section, taken approximately as indicated by the angle arrows and broken lines II—II in Fig. 1.

Fig. 3 is a central vertical section on the plane III—III in Fig. 1; and,

Fig. 4 is an end elevation of the truck side frame as viewed from the right-hand of Fig. 1 or looking towards the left-hand thereof.

In describing the form of this invention exemplified by the above captioned drawings here-with, specific terms will be employed for the sake of clarity, but it is to be understood that the scope of said invention is not thereby limited, each such term being deemed to embrace all

reasonable equivalents capable of performing the same function for an analogous purpose.

Referring more in detail to the drawings, there is typified a hollow truck frame 5 of compact and strong construction, the same embodying an upper compression portion 6 and a lower tension portion 7, with struts 8 interconnecting said portions at either side of the bolster window 9, while providing guide means for the end of the bolster 10, said bolster end including walls 11 paralleling the struts 8, and a pocket 12 in the underside. In addition, the truck frame 5 has end journal boxes 13 with cross-ties 14 spacedly therebelow, said ties embodying vertically directed ribs 15, directly below and in alignment with the axis of rotation of the truck wheels 16, each of which ribs includes a recess 17, whereby said ribs constitute guide fulcrums for a purpose hereafter explained. The journal boxes 13 are, preferably, strengthened by vertical webs 18 projecting outwards from and coplanar with the side walls 19 of the frame 5, as readily seen in Fig. 4, while it is noteworthy the tension portion 7 is extended into approximate registration with the circumferential path of rotation of the wheels 16 for a purpose hereafter clarified. In other words, the truck frame 5 is substantially of rectangular cross-section with the longitudinal side walls 19 merging into the journal boxes 13 and the cross-ties 14 therebelow, while said walls are provided with triangulate access openings 20, of substantial proportions, to each side of the bolster end 10; and in addition the walls 19 are reinforced by oppositely inclined ribs 21, intermediate the journal boxes 13 and the relatively expanded section 22, of the tension portion 7, below the bolster window 9, which is seen to best advantage in Fig. 2.

The bolster end 10 is sustained in the frame window 9, in accordance with this invention, by means of a semi-elliptic main spring 23 having at the mid-region a strap device 24 that holds its leaves together, with the slightly rounded top engaged in the recess 25 of a bearing plate 26 loose in the bolster end groove 12, hereinbefore referred to. Each end 27 of the main spring 23 reacts on spacedly aligned and partially underlying more flexible secondary springs 28, by engagement in the grooved upper part 29 of strap devices 30, centrally of said secondary springs. The inner ends 31 of the secondary springs 28 bear on fulcrum ribs 32, close to the center line of the truck frame 5, across the tension portion 7 intermediate the walls 19 of said frame, while the outer ends 33 of said secondary springs 28 similarly bear on the fulcrums 17 directly under the vertical center of the respective journal boxes 13. It will be clearly apparent that by forming the main and secondary springs 23, 28, respectively of sixteen leaves six-inch by one-half inch

thick, and six-inch by three-eighths inch thick stock, the secondary springs 28 will be substantially lighter and more flexible, whereby shocks originating at the wheels 16 are transmitted directly through the more flexible secondary springs 28 to the more substantial stiffer main spring 23, and hence through the bolster 10 to the car. As a result, it is self-evident that low-amplitude high-frequency shocks are absorbed by the secondary springs 28, whereas the high-amplitude 10 low-frequency shocks are absorbed by the main spring 23.

It is to be further noted that the secondary springs 28 are so positioned that they become inactive, by the respectively associated straps 30 contacting stop pads 34 at the ends of the frame tension portion 7, after a predetermined load which is well beyond the maximum axle capacity load, and thereafter the load is carried only by the main spring 23, whereas said main spring is 20 protected from over-stress by its strap 24 contacting a stop 35 centrally bridging the frame 5 spacedly above the tension portion 7 thereof.

It will be further understood that, with the springs 23, 28 arranged and mounted in series as hereinbefore stated, a helper spring effect is obtained, between said springs, which permits a greater over-solid load with a minimum of spring travel, while the stops 34 for the secondary springs 28 provide a safety means in the event of spring 30 failure.

From the foregoing, it will be evident that the herein described embodiment of the invention fully justifies the featuring aims set forth in the opening paragraphs of this specification, and that 35 changes in the minor details of the frame 5, and the relative proportions of the springs 23, 28, are contemplated, in adapting said invention to different types of railway trucks, without departing from the scope of the following claims.

Having thus described my invention, I claim:

1. In a truck of the type described, the combination of a hollow side frame including a bolster window and journal boxes; a bolster with an end in said window; lappingly related leaf springs serially mounted in the side frame, one of said leaf springs medially supporting the bolster end, for up-and-down movement in the frame window, and having its terminal parts reactively engaged centrally of the other leaf springs; and means whereby the last mentioned springs are individually fulcrumed at their ends proximately central within the side frame and directly below the journal boxes.

2. In a truck of the type described, the combination of a hollow side frame including a bolster window and journal boxes; a bolster with an end in said window; lappingly related leaf springs serially mounted in the side frame, one of said leaf springs medially supporting the bolster end, for up-and-down movement in the frame window, and having its terminal parts reactively engaged centrally of the other leaf springs; means whereby the last mentioned springs are individually fulcrumed at their inner ends proximately central within the side frame and at their outer ends directly below the journal boxes; and means effective to limit the travel of all of said springs as well as affording safety stops in the event of spring failure.

3. In a truck of the type described, the combination of a hollow side frame including a

bolster window, a lower tension portion, and journal boxes at the ends of said frame; a bolster with an end in said window; a main semi-elliptic spring with planarly aligned longitudinally spaced secondary similar springs serially mounted in the side frame; said main spring having a strap medially supporting the bolster, for up-and-down movement in the frame window, with its terminal parts reactively engaged on similar straps centrally of the secondary springs; spaced means medially across the frame tension portion with similar means directly below the journal boxes, said means respectively affording fulcrum support for the inner and outer termini of the secondary springs; and stops also on said tension portion effective to limit the travel of the secondary springs and to prevent over-stressing of the main spring.

4. The combination according to claim 3, wherein the truck hollow side frame is mainly of rectangular cross-section with triangulate access openings in the side walls adjoining the bolster window, and the tension portion of said frame is extended into approximate registration with the circumferential path of rotation of the truck wheels.

5. The combination according to claim 3, wherein the truck hollow frame longitudinal side walls merge into the journal boxes, the tension portion embodies a relatively expanded section below the bolster window, opposingly inclined ribs intermediate the journal boxes and said expanded section reinforce the side walls; the fulcrum supports for the inner termini of the secondary springs consist of ribs across the expanded section of the frame tension portion proximate the center of the truck frame, and the fulcrum supports for the outer termini of said secondary springs are in the form of inverted T-section cross-ties intermediate the frame side walls and directly below the axis of rotation for truck wheels having bearing in the journal boxes.

6. The combination according to claim 3, wherein the main semi-elliptic spring comprises a plurality of comparatively thick leaves, and the secondary springs consist of a considerably less number of relatively thinner leaves; whereby said main spring serves as the full load carrier with the secondary springs each operating as a helper or half-load carrier.

7. Springing, for truck hollow side frames including a window opening with a load sustaining bolster end movable up-and-down therein and longitudinally spaced journal boxes, comprising superposed serially associated semi-elliptic springs mounted in a common plane within the side frame, one of said springs centrally supporting the bolster end with its terminal portions reactively engaging the mid-region of the other of said springs, and means medially central within the side frame and directly below the center of the journal boxes affording fulcrum bearing for the ends of the secondary springs.

8. The combination of claim 7, wherein one of the superposed serially associated springs includes a strap having a rounded top engageable in a confronting recess at the underside of the bolster end, and the ends of said spring coated with grooves in the upper parts of similar straps centrally embracing the lower of said serially associated springs.

ISAAC M. CHAMBERS.
